UNITED STATES PATENT OFFICE.

LEWICKI J. LEON, OF WEST CHICAGO, ILLINOIS.

DESIGN FOR A BIRD CAGE.

Application filed January 8, 1927. Serial No. 20,308. Term of patent 14 years.

To all whom it may concern:

Be it known that I, LEWICKI J. LEON, a citizen of the United States, residing at West Chicago, in the county of Du Page and State of Illinois, have invented a new, original, and ornamental Design for a Bird Cage, of which the following is a specification, reference being had to the accompanying drawing, forming part hereof.

Fig. 1 is a perspective view of a bird cage showing my new design;

Fig. 2 is a vertical sectional view through the base of the cage, taken on line 2—2 of Fig. 1, to show the contour of the same in more detail than illustrated in Fig. 1; and

Fig. 3 is a diagrammatic front view illustrating the general outline or contour of the cage shown in Fig. 1.

I claim:

The ornamental design for a bird cage, as shown.

LEWICKI J. LEON.
